Primary Examiner—Melody N. Brown*Attorney, Agent, or Firm*—Ian C. McLeod; Mary M. Moyne[57] **CLAIM**

The ornamental design for an armrest attachment for use in a recreational vehicle, as shown and described.

DESCRIPTION

FIG. 1 is a right side elevational view of an armrest attachment showing my new design;
 FIG. 2 is a bottom plan view thereof;
 FIG. 3 is a front elevational view thereof;
 FIG. 4 is a left side elevational view thereof;
 FIG. 5 is a top plan view thereof;
 FIG. 6 is a rear elevational view thereof; and,
 FIG. 7 is a perspective view showing use of my armrest attachment in a recreational vehicle.
 The broken line showing of the lower portion in FIGS. 1 to 6 and the interior of the recreational vehicle in FIG. 7 is for illustrative purposes only and forms no part of the claimed invention.
